[57] CLAIM

The ornamental design for a cocktail table, as shown and described.

DESCRIPTION

FIG. 1 is a perspective view of a cocktail table showing my new design;

FIG. 2 is a top plan view thereof;

FIG. 3 is a side elevational view thereof; and

FIG. 4 is a bottom plan view thereof.

The appearance of the three sides not shown in FIG. 3 are the same in appearance as the side shown therein.
